UNITED STATES PATENT OFFICE.

JOB S. BRIGGS AND L. WRAY FALWELL, OF PROVIDENCE, RHODE ISLAND,
ASSIGNORS TO THE NATIONAL SAFETY GAS BURNER COMPANY, OF
PROVIDENCE, RHODE ISLAND, A CORPORATION OF NEW JERSEY.

GAS-BURNER.

SPECIFICATION forming part of Letters Patent No. 778,104, dated December 20, 1904.
Application filed March 24, 1904. Serial No. 199,814.

To all whom it may concern:

Be it known that we, JOB S. BRIGGS and L. WRAY FALWELL, citizens of the United States, residing at Providence, in the county of Providence and State of Rhode Island, have invented new and useful Improvements in Gas-Burners, of which the following is a specification.

Our invention relates to new and useful improvements in gas-burners; and its object is to provide mechanism of simple and inexpensive construction, whereby the flow of gas from the burner may be promptly established and by means of which the flow will be automatically shut off whenever the light is for any reason extinguished.

With the above and other objects in view the invention consists of a burner having a sliding valve therein which is adapted to open and close the passage extending through the burner. This valve is connected to a thermostat which extends over the tip of the burner and has a hooked arm adapted to be engaged by a valve-opening lever.

The invention also consists in the novel construction, combination, and arrangement of parts, as herein fully described, claimed, and illustrated in the accompanying drawings, in which—

Figure 1 is a side elevation of a burner constructed in accordance with our invention. Fig. 2 is a vertical section therethrough. Fig. 3 is an end elevation of the burner. Fig. 4 is a side elevation of the operating-lever detached. Fig. 5 is a plan view thereof. Fig. 6 is a side elevation of the lever-supporting bracket. Fig. 7 is a detail view of the blank from which said bracket is adapted to be formed. Fig. 8 is an elevation of the thermostat with its arm removed.

Referring to the drawings by numérls of reference, 1 is a burner having a tip 2, and arranged within this burner is a plug 3, provided with a passage 4, through which gas is adapted to be supplied to the tip. A recess 5 is formed within one side of the plug and tube 1, and slidably mounted therein is a pin 6, which forms a valve and which is adapted when pressed inward to close the passage 4.

This pin is held normally in its inner position by means of a bowed-spring strip 7, which extends over the tip and has a slot 8 in that portion thereof arranged above the tip. The end of the strip 7 which engages the pin 6 has a longitudinally-extending slot 9 therein, while the other end is secured to one side of the collar 10, which is bolted or otherwise secured to the upper portion of tube 1. An arm 11 extends laterally from the slotted end of strip 7 and has a hook 12 at its free end, which is arranged normally above a hook 13, extending from one end of the loop 14. This loop encloses the tube and is pivoted upon pins 15, which extend laterally from a collar 16, bolted or otherwise secured upon the tube 1. An arm 17 extends upward from the collar 16 and has a hook 18 at its upper end, to which is connected a coiled spring 19. The other end of this coiled spring engages an arm 20, which projects from loop 14 at the side thereof opposite hook 13, and a chain or other operating device 21 depends from the arm 20. A ring 22 is connected to the strip 10 and loosely encloses tube 1, so as to limit the lateral movement of said strip when the same is subjected to heat.

When it is desired to light the gas at the tip 2, the arm 20 is pulled downward by means of the chain 21, and the yoke 14 is caused to swing upon its pivot 15 and will press the hook 13 upward against arm 11. This arm will be pressed outward and will draw slide-valve 6 away from passage 4. Hooks 12 and 13 will engage each other, and the valve 6 will thus be held in open position. The gas is then free to flow from passage 4 and can be ignited at the tip 2. The heat from the flame will cause the expansion of the strip 7, which will act as a thermostat and will bend outward automatically and release the hooks 12 and 13 from engagement with each other. The spring 19 will then return the lever to its normal position and the valve 6 will be held open by the thermostat. Should the light be extinguished, the strip 7 will return automatically to its normal position and will press the valve 6 inward across the pas-

sage 4, and the flow of gas will thus be promptly stopped. In Figs. 1 and 2 we have shown the strip 7 provided with an inner reinforcing-strip 23. This inner strip is formed 5 of material which will rapidly expand when subjected to heat, thus insuring the lateral movement of the strip 7 when the gas is ignited.

In the foregoing description we have shown 10 the preferred form of our invention; but we do not limit ourselves thereto, as we are aware that changes may be made in the form, proportion, and minor details of construction without departing from the spirit or sacrificing 15 any of the advantages of the invention, and we therefore reserve the right to make such changes as fall within the scope of our invention.

Having thus described the invention, what 20 is claimed as new is—

1. The combination with a burner having a slide-valve therein, of a thermostat extending over the burner and connected to the valve, an arm extending from the thermostat, and a 25 valve-opening lever connected to the burner and separate from but adapted to engage the arm to lock the valve in opened position.

2. The combination with a gas-burner having a slide-valve therein, of a slotted thermostat secured to the burner and extending there- 30 over, said thermostat engaging the valve, a hooked arm extending from the thermostat, a spring-controlled lever connected to the burner, and a hook upon the lever for engag- 35 ing the arm.

3. A burner comprising a tube having a tip on one end thereof, a plug within the tube having a passage therethrough, a slide-valve within the plug and tube and normally closing the 40 passage, a longitudinally-slotted bowed thermostat secured to the tube and extending over the tip, said thermostat having a slotted end adjustably connected to the valve, a ring secured to the thermostat and loosely inclosing 45 the tube, and a pivoted lever connected to the tube and adapted to operate the thermostat to open the valve.

4. A burner comprising a tube having a tip on one end thereof, a plug within the tube having a passage therethrough, a slide-valve within the plug and tube and normally closing the 50 passage, a longitudinally-slotted bowed thermostat secured to the tube and extending over the tip, said thermostat having a slotted end

adjustably connected to the valve, a hooked 55 arm, extending from the thermostat, and a spring-controlled hooked lever mounted upon the tube and adapted to operate and engage the arm.

5. A burner comprising a tube having a tip 60 on one end thereof, a plug within the tube having a passage therethrough, a slide-valve within the plug and tube and normally closing the passage, a longitudinally-slotted bowed thermostat secured to the tube and extending over 65 the tip, said thermostat having a slotted end adjustably connected to the valve, a hooked arm extending from the thermostat, a loop inclosing and pivoted upon the tube, a hooked arm extending therefrom and adapted to bear 70 upon and operate the arm of the thermostat, a spring connected to the loop, and an operating device depending from the loop.

6. A burner comprising a tube having a tip 75 on one end thereof, a plug within the tube having a passage therethrough, a slide-valve within the plug and tube and normally closing the passage, a longitudinally-slotted bowed thermostat secured to the tube and extending over the tip, said thermostat having a slotted end 80 adjustably connected to the valve, a ring connected to the thermostat and loosely inclosing the burner, and means for operating the thermostat to open the valve.

7. A burner comprising a tube having a tip 85 on one end thereof, a plug within the tube having a passage therethrough, a slide-valve within the plug and tube and normally closing the passage, a longitudinally-slotted bowed thermostat secured to the tube and extending over 90 the tip, said thermostat having a slotted end adjustably connected to the valve, a ring secured to the thermostat and loosely inclosing the tube, a collar secured to the tube, a hooked arm thereon, a loop pivoted upon said collar 95 and inclosing the tube, a hooked arm thereon, a hooked arm upon the thermostat adapted to be engaged thereby, a spring connected at opposite ends to the loop and the arm of the collar, and an operating device connected to the 100 loop.

In testimony whereof we affix our signatures in presence of two witnesses.

JOB S. BRIGGS.
L. WRAY FALWELL.
